2 Sheets-Sheet 2

UNITED STATES PATENT OFFICE.

HARRY SELDOMRIDGE, OF CLINTON, INDIANA, ASSIGNOR OF ONE-HALF TO ANTHONY MARIETTA, OF CLINTON, INDIANA.

AUTOMOBILE JACK.

Application filed December 30, 1926. Serial No. 158,033.

This invention is an apparatus for raising automobiles from the floor of a garage or from the ground and supporting them firmly in an elevated position to permit workmen to have ready access to the chassis in order to make repairs, and the object is to provide a very simple, compact and strong mechanism whereby the automobile will be easily raised and firmly supported in the raised position and the mechanism braced against premature collapse. The invention is illustrated in the accompanying drawings and will be hereinafter fully set forth.

In the drawings:

15 Figure 1 is a plan view of an apparatus embodying the invention;

Fig. 2 is a side elevation, partly broken away, of the mechanism showing it in its collapsed position;

20 Fig. 3 is a side elevation showing the apparatus raised;

Fig. 4 is an end elevation;

Fig. 5 is a detail section on the line 5—5 of Fig. 3;

25 Fig. 6 is a detail perspective of a bearing block;

Fig. 7 is a detail of a portion of the switch-shifting bar.

In carrying out the invention, I provide a 30 pair of base bars or rails 1 which are of proper length and may conveniently be flat bars of strap metal having their ends upturned or formed into eyes 2 receiving fulcrum rods 3. These base bars or rails are placed upon 35 the ground or the floor of a garage and are held against relative movement by cross bars or beams 4 arranged at intervals and rigidly secured at their ends to the base rails. Bearing boxes or blocks 5 are provided having 40 transverse openings 6 in their lower portions accommodating the respective fulcrum rods 3 whereby the blocks will be supported. Longitudinally disposed openings or sockets 7 in the upper parts of the blocks constitute 45 bearings for a shaft 8 disposed upon the medial longitudinal line of the apparatus and having one end connected by a universal joint 9 with the driving shaft 10 which is preferably the armature shaft of an electric motor. 50 The motor may be of any approved type and is not illustrated as, in itself, it forms no part of the present invention; it may be arranged to conform to conditions at the place of installation so that it will be out of the way of 55 the vehicle being driven onto or from the jack

and will not interfere with the movements of the workmen. The shaft 8 is formed or equipped with worms or threads 11 at opposite sides of its center, the pitch of said worms or threads being reversed relative to each other. Fitted upon the worms 11 are nuts 12 so that the rotation of the shaft will cause the nuts to travel along the same in opposite directions, and to the opposite sides of each nut are pivotally attached the inner ends of 60 levers 13, the inner ends of links 14 being pivotally connected to the respective levers at the centers thereof, as shown at 15. The outer ends of the links 14 are pivoted upon the fulcrum rods 3, while the outer ends of the 70 levers 13 are pivotally engaged with cross rods 16, the ends of which project beyond the levers and are engaged in longitudinal slots 17 in lifting bars 18 which extend the full length of the apparatus and are intended 75 to support the automobile upon which repairs are to be made. Rollers 19 are mounted on the rods 16 to reduce frictional wear. The bars 18 may engage directly against the under sides of the axles of the vehicle so that the 80 weight of the vehicle will be carried directly by the said bars, and it will be noted upon reference to Fig. 2 that, when the device is collapsed, the said bars 18 will be close to the surface of the ground or the garage floor and 85 the automobile may be driven under its own power into position over the device without any interference with any of the parts of the same. It may be desirable, under some circumstances, to secure upon the upper sides of 90 the supporting bars 18 other bars of similar form which may have their ends downturned whereby they will constitute skids or runways to permit the vehicle to be driven onto the same so that the wheels will rest 95 thereon and a partial elevation of the vehicle be accomplished before the lifting apparatus is set in motion. It may be desirable in some instances to provide a trench to accommodate the driving shaft so that all parts of the apparatus will be disposed in a low plane and 100 obstruction to traffic will be minimized.

Spacing sleeves 19 are fitted upon the fulcrum rods 3 between the blocks 5 and the links 14 so that the relation of the parts will be 105 maintained. In order that the motor will be stopped when the apparatus is either fully expanded or fully collapsed, I provide a release bar 20 slidably mounted in guides 21 on braces 4 directly under the shaft 8, and on 110

said bar are lugs or projections 22 at opposite sides of the superjacent nut 12 and in the path of the nut so as to receive impact therefrom as the nut approaches the limit of 5 its travel. The motor is equipped with a double-throw switch which closes the circuit in its central position but breaks the circuit when moved to either side. As the nut 12 approaches the end of its prescribed travel 10 in either direction, it will impinge upon a lug 22 and thereby actuate the bar 20 to open the switch.

It is thought the operation will be readily understood from the foregoing description, 15 taken in connection with the accompanying drawings. The device is normally collapsed, as shown in Figs. 1 and 2, wherein the lifting levers 13 are disposed at the outer sides of the links 14 and at the inner sides of the base 20 rails 1, the bars 18 being disposed at the outer sides of the levers and the nuts 12 being at the inner limits of their movement. A vehicle having been brought into position over the apparatus, the motor is started and the 25 driving shaft 10 thereby caused to rotate. The rotation of the said shaft will be imparted to the shaft 8 and the rotation of said shaft will at once effect outward travel of the nuts 12. It will be observed that the 30 lifting levers 13 are slightly bent or in the form of very shallow V's so that the inner ends of the levers extend upwardly from their pivotal connections with the nuts and, as a result of this arrangement, the outward 35 travel of the nuts will exert an upward push against the pivotal connections 15 between the levers and the links 14. The outer ends of the levers will, consequently, be caused to swing upwardly and impart lifting movement to the rails or bars 18 so that the vehicle 40 engaged by the rails will be raised as desired. As the levers thus swing upwardly, the links 14 will also swing upwardly and outwardly and eventually will assume positions nearly 45 vertical whereby they will brace the levers and aid in supporting the vehicle off the ground. When the vehicle is fully raised, one nut 12 will impinge against the outer lug 22 so that the motor will stop and the rotation 50 of the shafts 10 and 8 will thereupon cease. The threaded engagement of the nuts and the shaft 8 will thereupon serve as brakes to aid in maintaining the vehicle supporting bars 18 in their raised position so that premature 55 collapse of the toggle connection provided by the levers and the links will be prevented. When the vehicle is to be again lowered, the motor is started in the usual manner to impart 60 reverse rotation to the shafts 10 and 8 and the nuts 12 will then, of course, travel inwardly so that the levers and links will be re-

turned to their initial position illustrated in Figs. 1 and 2.

My improved apparatus is very simple and compact and will operate easily and efficiently at all times. By its use, all manual labor in raising a vehicle from the ground or a floor is eliminated and the vehicle will be supported in an elevated position so that workmen inspecting or repairing it will have 65 easy access to all parts of the same. In order to minimize wear and increase the ease of operation, the pivotal connections between the several parts and the bearings of the several shafts are preferably of the anti-friction type 70 but the particular form of the bearings is immaterial.

Having thus described the invention, I claim:

1. The improved vehicle jack comprising a 80 pair of base bars, rigid connections between the same, transverse fulcrum rods secured on the base bars at the ends thereof, a rotatable worm shaft disposed between and parallel with the base bars and having relatively reversed threads at opposite sides of its center, nuts fitted on said threads, lifting levers pivoted to the respective nuts and extending therefrom toward the respectively adjacent ends of the base bars, said levers being of 85 shallow V-shape in the direction of their length, lifting rails carried at their ends by the free ends of the lifting levers, and links pivotally fitted at their outer ends on the fulcrum rods and having their inner ends pivoted to the respectively adjacent lifting levers at the bends in the latter. 90

2. The improved vehicle jack comprising a pair of base bars, rigid connections between the same, transverse fulcrum rods secured on 100 the base bars at the ends thereof, a rotatable worm shaft disposed between and parallel with the base bars and having relatively reversed threads at opposite sides of its center, nuts fitted on said threads, lifting levers pivoted to the respective nuts and extending 105 therefrom toward the respectively adjacent ends of the base bars, lifting rails carried at their ends by the free ends of the lifting levers, links pivotally fitted at their outer 110 ends on the fulcrum rods and having their inner ends pivoted to the respectively adjacent lifting levers, a release bar slidably mounted below and parallel with the worm shaft, and projections on said bar at opposite sides of the adjacent nut on the worm shaft and in the path of said nut whereby to effect shifting of the bar for arresting rotation of the shaft. 115

In testimony whereof I affix my signature.

HARRY SELDOMRIDGE. [L. S.]
